UNITED STATES PATENT OFFICE

99,663

DESIGN FOR A RUG OR SIMILAR ARTICLE

Henry F. Jones, Calhoun, Ga., assignor to Jones
Roofing and Supply Company, Inc., Calhoun,
Ga., a corporation of Georgia

Application March 18, 1936, Serial No. 61,682

Term of patent 3½ years

To all whom it may concern:

Be it known that I, Henry F. Jones, a citizen of the United States, residing at Calhoun, county of Gordon, State of Georgia, have invented a new, original, and ornamental Design for a Rug or Similar Article, of which the following is a specification, reference being had to the accompanying drawing, forming a part thereof.

The drawing is an elevation showing the rug or similar article.

The rug or similar article has the average thickness of an ordinary tufted or woven rug which is approximately one-half inch.

I claim:

The ornamental design for a rug or similar article, as shown and described.

In testimony whereof, I have hereunto affixed my signature.

HENRY F. JONES.
